GRINDING ATTACHMENT

Constantine Melidoni and Harold Gass, New York, N. Y., assignors to Van Norman Company, Springfield, Mass., a corporation of Massachusetts

Application April 19, 1945, Serial No. 589,148

7 Claims. (Cl. 51—231)

This invention relates to an attachment for grinding machines whereby cylinder heads of engines and the like are ground or resurfaced.

An object of this invention is to provide a self-contained grinding attachment which may be mounted as a unit on a grinding machine table, the said attachment comprising a stationary frame having two fixed and spaced-apart guideways and a pinion gear and handwheel rotatably supported thereon.

Another object of this invention is to provide a slidable frame mounted on the stationary frame, the slidable frame having a rack gear in meshed engagement with the pinion gear and being reciprocable relative to the stationary frame by rotation of the handwheel and pinion gear.

Another object of this invention is to provide a gripping frame fixedly attachable in alinement with the slidable frame and having four jaws pivotally mounted thereon, the said jaws extending below the gripping frame and being adapted to be moved into clamping engagement with a cylinder head lying upon the table of the grinding machine.

Another object of this invention is to provide dowel pins in the slidable frame and means whereby the dowel pins may be placed in engagement with the gripping frame so as to cause the gripping frame to be movable as a unit with the cylinder head while supported by the stationary frame.

Another object of this invention is to provide a two-part detachable hinge, the said hinge having one part fixed to the slidable frame and the other part fixed to the stationary frame, the two hinge parts being so disposed as to permit slidable engagement with each other after disengagement of the dowel pins, the hinge serving to swing the gripping frame jointly with a cylinder head from the table of the grinding machine to a substantially vertical position at one side of the slidable frame and so as to make the ground surface visible to the operator whereby the operator can easily determine as to the necessity of taking a further cut on the cylinder head.

With the above and other objects in view, the invention will be hereinafter more particularly described, and the combination and arrangement of parts will be shown in the accompanying drawings and pointed out in the claims which form part of this specification.

Reference will now be had to the drawings, wherein like numerals of reference designate cor-

responding parts throughout the several views, in which:

Figure 1 is a plan view of the grinding attachment mounted on the table of a grinding machine.

Figure 2 is an end view of the grinding attachment in operative position.

Figure 3 is an end view, the same as shown in Figure 2, with the gripping frame swung into vertical position.

Figure 4 is a cross-sectional view, the section being taken as on line 4—4 in Figure 3.

Figure 5 is a cross-sectional view, the section being taken as on line 5—5 in Figure 4, and showing arms for aligning the gripping and slidable frames.

In the illustrated embodiment of the invention, the numeral 10 indicates a self-contained grinding attachment comprising a rectangular frame 11 by means of which the attachment is fixed to the upper surface or table 12 of a grinding machine 13.

The grinding machine has a horizontally positioned grinding wheel 14 secured to a vertically movable shaft 15. By adjusting the shaft 15, the grinding wheel is brought upwardly into grinding relation with the lower surface of a cylinder head 16 lying upon the table 12.

In accordance with present practice in the art, 30 a cylinder head to be resurfaced by grinding its lower face is placed upon the grinding table 12 and held against the grinding wheel 14 merely due to the weight of the cylinder head and it is impossible to take a grinding cut of more than 35 one thousandth of an inch.

With the clamping and holding attachment herein disclosed it is possible to take a grinding cut of one-sixty-fourth of an inch in one operation and accordingly the rate of production is 40 about five times as great as heretofore. Additionally, with the use of the grinding attachment 10, the grinding is perfectly uniform and performed with precision, which was not possible heretofore. The grinding machine 13 is well 45 known in the art and not part of the present invention and accordingly needs no further description.

The fixed frame 11 comprises elongated horizontal bars or base members 17, 17, having vertical end portions or aprons 18, 18, which extend downwardly below the table 12. Bars 19, having guideways 20 are fastened to the base members 17. The guideways face each other.

A slidable rectangular frame 21 is mounted on 55 the fixed frame 11. The frame 21 has two side

walls 23 extending lengthwise and two side walls 24, which extend crosswise of the fixed frame 11. The frame 21 has slide bars 25 fixed to its lengthwise side walls 23. The slide bars 25 fit into the guideways 20 in slidable relation. A rack gear 26 is suitably fixed to one of the slide bars 25 in any suitable way such as by welding.

A bearing 27 is fixed to an extension 28 of the fixed frame 11 and supports a shaft 29. A pinion gear 30 is fixed at one end of the shaft 29 and is in meshed engagement with the rack gear 26. A handwheel 31 is fixed to the outer end of the shaft 29. By rotating the handwheel, the pinion gear 30 reciprocates the rack gear 26 and the frame 21.

A rectangular gripping frame 35 having a width slightly larger than the width of the slidable frame 21, is supported upon the slidable frame. The transverse sides 36 of the gripping frame 35 have through apertures 37 at each end thereof. Four pivotal gripping jaws 38 have pin extensions 39 mounted in the apertures 37.

Bolts 40 threaded in the lengthwise walls of the gripping frame and positioned in alignment with the gripping jaws 38 serve for moving the jaws into clamping engagement with the cylinder head 16 lying upon the table 12.

In practice, the distance between the bolts 40 and the pin extensions 39 is made considerable so as to provide leverage to augment the gripping power of the jaws against the cylinder head.

The slidable frame 21 has outwardly projecting dowel pins 41. The dowel pins are adapted to be brought into engagement with openings 42 in aligning arms 43 which are fixed to the gripping frame 35. This engagement causes the slidable frame and the gripping frame to come into unitary relation.

Fixed to the rear surface of one of the lengthwise sides 23 of the slidable frame 21, is a hinge element 45 having an elongated aperture 46. Fixed to the rear wall of the gripping frame 35 is a co-acting hinge element 47 having a pintle 48 positioned in alignment with the aperture 46 in the hinge element 45.

Under practical operating conditions, or in dowel pin engaging position, the hinge element 45 is considerably spaced from the pintle 48 to permit sliding movement of the gripping frame to first disengage the gripping frame from the dowel pins and thereby release the gripping frame from engagement with the slidable frame.

Further sliding movement of the gripping frame causes the pintle 48 to come into engagement with the co-acting aperture 46 in the hinge element 45. In this position, the hinge elements are in engagement and it is possible to swing the gripping frame 35 jointly with the cylinder head 16 to a position rearward of the slidable frame 21, and in which position the cylinder head assumes a substantially vertical position which permits the operator to easily examine the ground surface of the cylinder head and to determine whether a further regrinding is necessary.

It is to be noted that bolts 50 are threaded in the corner portions of the gripping frame 35 and are respectively positioned in alignment with the midportion of the side walls 23 to bring the frames 21 and 35 into fixed relation.

After a grinding operation is completed, the operator loosens the bolts 50. He is then in a position to move the gripping frame away from the dowel pins 41 and to swing the gripping frame

35 upon the hinge and bring the ground surface of the cylinder head into perpendicular relation with the table 12 of the grinding machine. If the operator finds further grinding necessary, he swings the gripping frame 35 with the attached cylinder head back into grinding position. The operator then raises the grinding wheel 14 slightly above the previous grinding level and repeats the operation of grinding the cylinder head. The operator then swings the cylinder head again to the rear of the slidable frame and re-examines the ground surface. The ground cylinder head or any other article requiring grinding is in supported relation while being inspected.

15 If he finds the ground surface to be properly ground he again lowers the gripping frame 35 into engagement with the slidable frame 21. The operator then moves the gripping frame 35 away from engagement with the dowel pins 41 and causes the gripping frame to become clear of interlocking engagement with the slidable frame 21. He is then in a position to remove the ground cylinder head from the grinding machine.

20 For the purpose of taking care of cylinder heads of different sizes we have provided a plurality of spaced-apart apertures 37 at each end of the transverse sides 36 of the gripping frame 35. This arrangement permits the operator to pivotally mount the gripping jaws 38 selectively in either of the apertures 37, whichever suits the particular cylinder head to be ground.

25 It is further to be noted that the pintle 48 of the hinge 47 is slightly bevelled at its free outer end and that the elongated aperture 46 in the hinge element 45 has a bevelled end portion. These bevelled portions facilitate the engagement of the hinge elements without the necessity of looking for the proper position so as to engage the complementary hinge element.

30 It is also to be noted that the aligning arms 43 are in close fitting relation with the outer faces of the slidable frame 21 and that this causes the interengagement of the hinge parts to take place automatically.

35 As best shown in Figure 4, it will be seen that rectangular openings 51 are provided in the side walls 23 of the slidable frame 21, to permit the aligning arms 43 to clear the rear wall 23 when the gripping frame 35 is swung into vertical position for the inspection of the ground cylinder head, etc.

40 As best shown in Figure 5, it will be seen that the aligning arms 43 have their openings 42 of a size adapted to receive the dowel pins 41 for securing the gripping frame and slidable frame in unitary relation.

45 In accordance with the patent statutes we have described and illustrated the preferred embodiment of our invention, but it will be understood that various changes and modifications can be made therein without departing from the spirit of the invention as defined by the appended claims.

50 We claim:

55 1. A grinding attachment comprising a stationary frame having two fixed and spaced-apart guideways, said stationary frame being adapted for mounting on the table of a grinding machine, a frame slidable on said stationary frame, said frames having gear means whereby said slidable frame may be reciprocated in relation to said stationary frame, a gripping frame fixedly attachable in alignment with said slidable frame and having a plurality of jaws pivotally mounted thereon, said jaws extending below said gripping

frame and being adapted to be moved into gripping engagement with a cylinder head lying upon said table, and two-part detachable hinge means respectively fixed to said slidable frame and to said stationary frame to permit swinging of said gripping frame jointly with said cylinder head from said table to a substantially vertical position into full visibility for inspection.

2. A grinding attachment comprising a stationary frame having two fixed and spaced-apart guideways, said stationary frame being adapted for mounting on the table of a grinding machine, a frame having slides fitting in said guideways and being thereby slidable on said stationary frame, said frames having gear means whereby said slidable frame may be reciprocated in relation to said stationary frame, a gripping frame fixedly attachable in alignment with said slid-able frame and having a plurality of jaws pivotally mounted thereon, said jaws extending below said gripping frame, means for moving said jaws into gripping engagement with a cylinder head lying upon said table, and two-part detachable hinge means respectively fixed to said slidable frame and to said gripping frame to permit swinging of said gripping frame jointly with said cylinder head from said table to a substantially vertical position into full visibility for inspection.

3. In a grinding attachment comprising a stationary frame having two fixed and spaced-apart guideways, said stationary frame being adapted for mounting on the table of a grinding machine, a frame having slides fitting in said guideways and being thereby slidable on said stationary frame, said frames having gear means whereby said slidable frame may be reciprocated in relation to said stationary frame, a gripping frame fixedly attachable in alignment with said slidable frame and having a plurality of jaws pivotally connected at their upper ends to the gripping frame to swing inwardly therein, said jaws extending below said gripping frame and means threaded through the sides of the gripping frame to engage the outer faces of the jaws at a point substantially below their pivots for moving said jaws into gripping engagement with a cylinder head lying upon said table.

4. In a grinding attachment comprising a stationary frame having two fixed and spaced-apart guideways, said stationary frame having aprons extending downwardly below said guideways and being adapted for mounting on the table of a grinding machine, an elongated frame having slides fitting in said guideways and being slidable on said stationary frame over said aprons and beyond the ends of said table, said frames having co-acting gear means whereby said slidable frame may be reciprocated in relation to said

stationary frame, a gripping frame fixedly attachable in alignment with said slidable frame and having a plurality of gripping jaws pivotally mounted thereon, said jaws extending below said gripping frame and means threaded through the sides of the gripping frame and engaging the outer faces of the jaws at points substantially spaced from their pivots for moving said jaws into gripping engagement with a cylinder head lying upon said table.

5. In a grinding attachment comprising a stationary frame having two fixed guideways, said stationary frame having aprons extending downwardly below said guideways and being adapted for mounting on the table of a grinding machine, an elongated frame having slides fitting in said guideways and being slidable on said stationary frame over said aprons and beyond the ends of said table, said frames having co-acting gear means whereby said slidable frame may be reciprocated in relation to said stationary frame, a gripping frame fixedly attachable on said slidable frame and having a plurality of gripping jaws pivotally mounted thereon, said jaws extending below said gripping frame, threaded means in said gripping frame for moving said jaws into gripping engagement with an article to be ground, and means for swinging said article for inspection while in supported relation,

6. In a grinding attachment comprising a stationary frame having two fixed guideways, said stationary frame having aprons extending downwardly below said guideways and being adapted for mounting on the table of a grinding machine, an elongated frame having slides fitting in said guideways and being slidable on said stationary frame over said aprons and beyond the ends of said table, said frames having co-acting gear means whereby said slidable frame may be reciprocated in relation to said stationary frame, a gripping frame fixedly attachable on said slidable frame and having a plurality of gripping jaws pivotally mounted thereon, said jaws extending below said gripping frame, threaded means in said gripping frame for moving said jaws into gripping engagement with an article to be ground, said slidable frame having a hinge element, said gripping frame having a hinge element co-acting with said hinge element on said slidable frame for swinging said article for inspection while in supported relation.

7. The invention as defined in claim 6, wherein said hinge elements are disengageable to permit said gripping frame to be released from engagement with said slidable frame.

CONSTANTINE MELIDONI.
HAROLD GASS.
